Specification of Letters Patent.

Patented May 12, 1914.

Application filed November 11, 1913. Serial No. 800,370.

To all whom it may concern:

Be it known that I, OTTO H. L. WERNICKE, a citizen of the United States, residing at Grand Rapids, in the county of Kent and 5 State of Michigan, have invented a new and useful Improvement in Fire-Resisting Cabinets, of which the following is a specification.

My invention relates to an improvement 10 in the insulation for the class of safes known as "safe-cabinets." This term signifies a double-walled sheet-metal type of safe, which has been extensively adopted into commercial use within the past few years 15 because it is inexpensive and capacious, and light in weight compared with the ordinary safe containing more or less massive insulation, in which the exothermic action of heat 20 is objectionable because of the danger there- of to the safe-contents.

The more important advantages which it 25 has been the aim of manufacturers of this type of safe to attain are low cost, lightness in weight and efficiency in retarding heat. 30 For the last-named attainment, organic materials, such as straw, strawboard, and the like, and inorganic materials, such as asbestos, plaster of Paris, and the like, have been employed for lining or filling the spaces 35 between the safe-walls. These, however, in the various forms in which they have been provided, have proved insufficient for their fireproofing purpose, since while they have been found to resist an extraordinary de- 40 gree of heat, they do so only for a short time, ranging from about five minutes up to, possibly, thirty minutes under temperature ranging from about 1000° F. to about 2000° F.; and the gases generated by the action of 45 the heat on the insulating materials tend to distort the sheet-metal walls and thereby admit destructive heat to the safe-contents.

The primary object of my invention is, 50 while retaining the important advantages of low cost and light weight of the structure, to provide a form of insulating material of the kind referred to, in the space between the sheet-metal safe-walls, which shall serve to greatly enhance, over such insulation as 55 hitherto used for the purpose, the retardation of heat through the walls.

In the accompanying drawings, which

illustrate my invention in a preferred form of its embodiment, Figure 1 is a view in plan section of a safe provided with my improvement; Fig. 2 is an enlarged, broken perspective view showing my improved insulation provided as a filling for the space between the safe-walls, and Fig. 3 is an enlarged view of the construction of seam employed for yieldingly joining the rear wall and side walls of the safe. .

The inner walls 4 and outer walls 5 of the entire structure, including those of the hingedly-folding doors 6, are formed of 65 sheet-metal and spaced apart, as shown. Details of construction shown in Fig. 1 require no description in this connection, since they form no part of the present invention.

The spaces between the walls are provided 70 with a filling 7, extending from wall to wall, of strawboard, each board comprising a central corrugated section 8 between outer flat sections 9, which are coated on their outer surfaces with a light, absorbent, incom- 75 bustible material 10 containing water of crystallization, such as gypsum, which may be applied in suspension or solution with a brush, to the thickness of about one-sixteenth of an inch, more or less; and the strawboard 80 is previously treated, by immersion or otherwise, and subsequent drying, with a deliquescent substance, such as a solution of chlorid of calcium or magnesium. While the substances specified are preferred for my 85 purpose, other chemical substances having similar properties may be used. The result is a light-weight, low-cost insulator of superior heat-retarding properties. The corrugations in the strawboard, or other forms 90 of interstices to render it light, provide a multiplicity of dead-air spaces distributed throughout the filling; and the light organic structure, when coated with the porous in- 95 organic material, is stable and will not shrink under the influence of heat, but fills the space between the walls and requires no means of attachment thereto nor bracing. In case of fire, water distilled by the heat, 100 from the outer layers of inorganic and organic materials is absorbed by the next layers, whereby the water acts as a wet blanket on such next, until the moisture vaporized from the preceding layers is com-

bined and taken up by the strawboard of the next succeeding layer; and the vaporization thus progresses, while the heat continues, from the outermost layers through the entire filling. Thus each layer progressively absorbs the moist vapors released from the preceding layer by the progress of the destructive distillation of the organic material and release of the water of crystallization, until finally the strawboard of the inner layers becomes wet and soggy. In that condition of the light, corrugated strawboard it would mash and collapse, were it not for the relatively-thin alternating coatings 10 and the absence of large voids or of a large dead-air space in the structure. Moreover, the coatings 10 being distributed throughout the filling prevent collapsing of the structure which, in case of fire, provides alternate 20 layers of the strawboard for carbonization by the heat, if it be sufficiently intense and enduring, after distillation of the moisture; and the carbonized strawboard, which is itself a good heat-retarder, is held intact by 25 the coatings against crumbling.

By the deliquescent treatment of the organic material of the safe-lining, its insulating action is materially increased, since the amount of water to be vaporized by heat is 30 greatly augmented, and the lining-structure produces progressive accumulation, absorption, and revaporization of this moisture, thereby increasingly checking the progress of the heat through it. The coatings 10, 35 moreover, besides exerting on the strawboard the sustaining effect referred to, contribute from their contained water of crystallization additional vapors to increase the yield of moisture from the lining under the 40 action of heat in case of fire.

The seams 11 formed of interlocking joints between the adjacent edges of the outer rear wall and side-walls of the safe, while sufficiently tight to be proof against 45 the admission from without of dangerous quantities of air into the zones of highest temperature in the filled spaces, which might ignite or explode gases generated therein, are loose enough to permit the expanding gases of the superabundance of 50 moisture, as steam, to escape and thus prevent such accumulation of the pressures as would tend to distort the walls and admit the heat into the interior of the safe to injure or destroy its contained papers, fabrics and the like delicate contents. In this connection it should be borne in mind that while 55 the temperature to which a safe is subjected in a fire seldom, according to underwriter experts, exceeds the temperature of 1500° F. the exothermic after effect from the safe itself or debris often continues for hours at destructive temperatures. Obviously, therefore, where insulating materials of great volume, density and conduc-

tivity are employed, though at first serving to retard the progress of heat, they later (after the fire is out) continue to radiate the absorbed or stored heat in all directions; so that an effective insulator of light and comparatively non-conducting materials and possessing the properties herein described affords the additional advantage of providing the better protection against destruction by such subsequent exothermic action. As 70 will therefore be apparent, by means of my improved insulation between safe-walls, there is provided, in case of fire, an abundance of moisture to retard the progress of the heat to the contents of the safe, and to 75 bring about the destructive distillation with a certain amount of resultant water-vapor a comparatively high temperature is required. By rendering the organic material employed deliquescent and coating it with 80 organic material containing much water of crystallization, while the temperature necessary to cause destructive distillation does not change appreciably, if at all, the amount of heat required to raise the material to the 85 temperature required for effecting the distillation is considerably increased because the vapor of water combined with or taken up by the chemical requires heat to drive it off before that heat can begin to act with 90 destructive effect upon the organic matter. The water-vapor formed both from the decomposition of the chemical and, later, from the destructive distillation of the organic matter and the added water released from 95 the organic matter, holds and retards the temperature at or near the boiling point of water until these vapors are driven off.

I realize that considerable variation is possible in the details of construction thus 100 specifically shown and described, and I do not intend by illustrating a single, specific or preferred embodiment of my invention to be limited thereto; my intention being in the following claims to claim protection for all 105 the novelty there may be in my invention as broadly as the state of the art will permit.

What I claim as new and desire to secure by Letters Patent is—

1. An insulating filling for fire-resisting 110 cabinets, comprising a plurality of layers of organic material, the outer surfaces of each of said layers being provided with a sustaining coating of inorganic material, and intermediate layers connecting said outer surfaces and formed to provide air spaces between said outer surfaces.

2. An insulating filling for fire-resisting 115 cabinets, comprising sheets of corrugated straw-board provided with outer flat surfaces, with sustaining coatings of inorganic material applied to said flat surfaces.

3. An insulating filling for fire-resisting 120 cabinets, comprising corrugated sheets of organic material provided with outer flat sur- 130

faces, with sustaining coatings of inorganic material applied to said flat surfaces.

4. An insulating filling for fire-resisting cabinets, comprising sheets of corrugated organic material provided with outer flat surfaces and chemically treated to augment its natural water-absorbing capacity, and pro-

vided on its outer flat surfaces with sustaining coatings of inorganic material.
